UNITED STATES PATENT OFFICE

152,809

DESIGN FOR A PRESSURE CONTROL
REGULATORWilbur J. MacCauley, Santa Monica, Calif., as-
signor to H. E. Lynn & Company, Inc., Santa
Monica, Calif., a corporation of CaliforniaApplication September 16, 1947, Serial No. 141,443
Term of patent 14 years

(Cl. D78—1)

To all whom it may concern:

Be it known that I, Wilbur J. MacCauley, a citizen of the United States, residing at Santa Monica, in the county of Los Angeles, State of California, have invented a new, original, and ornamental Design for a Pressure Control Regulator, of which the following is a specification, reference being had to the accompanying drawing, forming a part thereof.

Figure 1 is a top plan view of a pressure control regulator, embodying my new design.

Figure 2 is a side elevational view thereof.

Figure 3 is a front or rear elevational view thereof.

Figure 4 is a bottom plan view on a smaller scale.

I claim:

The ornamental design for a pressure control regulator, substantially as shown.

WILBUR J. MACCAULEY.
